UNITED STATES PATENT OFFICE.

JOHN E. PRACNY, OF WATERBURY, CONNECTICUT, ASSIGNOR TO THE E. J. MANVILLE MACHINE COMPANY, OF WATERBURY, CONNECTICUT, A CORPORATION OF CONNECTICUT.

ROLL FEED FOR METAL-HEADING MACHINES.

Application filed April 6, 1927. Serial No. 181,341.

Stock in the form of a rod or a continuous coil of wire is commonly fed into machines in which it is swaged, headed or punched, by rolls that grip the stock and are 5 intermittently rotated to advance the end of the stock to the operating tools. The present invention relates more particularly to means provided for separating the feed rolls of such machines whereby the operator is 10 enabled to easily pull out the end of a coil or rod and insert the end of another bundle of stock.

The object of the invention is to arrange a simple and convenient means which can be 15 quickly manipulated with but little effort for releasing the grip of the feed rolls upon the stock.

This object is attained by mounting the shaft which carries one of the feed rolls and 20 is provided with a rotating gear, in a pillow block that at one end is pivoted in its support and at the other end engaged by a cam, having an operating handle, in such manner that by turning the handle to one position 25 the cam swings the pillow block and slightly separates one roll from the other, and when the handle is turned to another position the cam allows the pillow block to be returned by a spring to its normal position in which 30 the rolls will grip and feed stock.

In the accompanying drawings Fig. 1 shows a side elevation of a roll feed mechanism which embodies this invention. Fig. 2 shows a front view of the mechanism with 35 one of the feed rolls broken away. Fig. 3 is a detail section showing the pivoted pillow block and the shaft with the movable feed roll and rotating gear carried thereby, also the roll closing spring and opening cam.

40 The feed mechanism illustrated is carried by a bracket 1 designed to be fastened to the frame 2 of the heading or similar machine with which it is to be used. Supported in suitable bearings in the lower part of the bracket is a shaft 3 that is adapted to be intermittently rotated by the mechanism usually employed for that purpose. A feed roll 4 is fastened to this shaft on one side of the bracket and a spur gear 5 is fastened to 45 the shaft on the other side of the bracket. The complementary feed roll 6 and spur gear 7 are fastened to a shaft 8 which is 50 rotatably held in bearings 9 in a pillow block 10. This pillow block is mounted in an opening in an upper part of the supporting 55 bracket. A pivot bolt 11 that passes through the bracket near the spur gear retains one end of the pillow block, while beneath the feed roll end of the block is a cam 12 which is fastened to a spindle 13 that turns in the 60 bracket and on its outer end has a hand lever 14. A spring 15 is arranged in the upper part of the bracket so as to bear down upon the swinging or feed roll end of the 65 pillow block. The tension of this spring is regulated by a screw 16 that is provided with handle bars 17 and that is threaded through the top of the bracket and thrusts against a plate 18 which rests upon the top of the spring. A lock nut 19 having a 70 handle 20 is turned on the tension screw for the purpose of preventing the screw from turning after the required tension of the spring is obtained. A guide bushing 21 is arranged tangentially to the meeting point 75 of the feed roll peripheries to guide the stock between the rolls.

When it is desired to start a piece of stock into the machine or remove a piece of stock from the machine to which this feed mechanism is applied, the hand lever is turned and the cam rotated so as to lift the swinging end of the pillow block and thus raise the upper feed roll the slight distance necessary to prevent the rolls from gripping the stock. 80 After the end of a length of stock has been entered through the guide bushing and passed between the rolls the hand lever is turned and cam rotated so as to allow spring to force the pillow block down and cause the 85 rolls to grip the stock with the required feeding tension. Although the tension of the spring is quite heavy, in order that the rolls may properly grip and feed the stock, the frictional grip of the rolls on the stock may 90 be instantly released with but slight effort by simply turning the hand lever which rotates the cam that causes the separation of the rolls and when the handle is turned back the normal feeding pressure is resumed. 95 For the purpose of description the member that is provided for swinging the pillow block against the tension of the spring and separating the feed rolls, is termed a "cam".

It is to be understood however that this term includes an eccentric as illustrated in the drawings.

The invention claimed is:

- 5 A roll feed mechanism comprising a bracket, a shaft having an attached feed roll and rotating gear mounted in the bracket, a pillow block pivotally attached to the bracket and carrying a shaft having an attached feed roll and rotating gear, a spring
- 10

thrusting against the upper face of the pillow block adjacent to the feed roll carried thereby, a screw arranged to tension the spring against the pillow block, a cam adapted to engage the under face of the pillow block adjacent to said feed roll, and a manually operated lever for turning the cam into and out of engagement with the pillow block.

JOHN E. PRACTNY.
